UNITED STATES PATENT OFFICE.

WILLIAM G. M. KEIGHLEY AND HARRY NETHERWOOD, OF HUDDERSFIELD, ENGLAND, ASSIGNORS TO THE COTTON CORD AND VELVET CUTTING MACHINE COMPANY, LIMITED, OF HUDDERSFIELD, ENGLAND.

MACHINE FOR CUTTING THE PILE OF FABRICS.

SPECIFICATION forming part of Letters Patent No. 790,577, dated May 23, 1905.

Application filed January 13, 1905. Serial No. 240,879.

To all whom it may concern:

Be it known that we, WILLIAM GEORGE MACGREGOR KEIGHLEY and HARRY NETHERWOOD, subjects of King Edward VII of Great Britain, residing at Huddersfield, in the county of York, England, have invented certain new and useful Improvements in Machines for Cutting the Pile of Woolen, Cotton, Velvet, or Like Corded Fabrics, of which

10 the following is a specification.

This invention has reference to machines for cutting cotton cords and velvets or like corded pile fabrics, and particularly to the mechanism for controlling the card-covered feed-roller to which the fabric is first conducted on entering the machine and with the periphery of which it is brought into full contact by suitably-disposed carrier or guide rollers, such a machine forming the subject-matter of

20 United States Patent No. 462,356.

The fabric to be cut is, as is well known to those skilled in the art, made endless in order that it may be traversed through the machine the requisite number of times to admit 25 of each race being cut, and it is conducted under and over guide-rollers to the feeding end of the machine, thence down an inclined table to the card-covered feed-roller, and over the back rail to the tension-roller, between 30 which and the said rail the knife or knives operate to cut the pile, the fabric on leaving the tension-roller being carried to a "scray" under the machine, on which it is cutted, and then passes forward under and over the 35 guide-rollers to the card-covered feeding-roller again.

The card-covered roller is driven by the frictional contact of the fabric, which is drawn through the machine by the positively-driven 40 tension-roller. By a belt, cord, or strap connection between the tension-roller or an adjacent driven shaft and a pulley mounted loosely on the axis of the card-covered feed-roller and rotatively engaged therewith in the 45 forward direction of its motion by a catch on the pulley taking into a tooth on a ratchet-wheel fast on the card-covered roller-shaft

the speed of the card-covered roller is retarded to approximately one-half that of the tension-roller in order that the fabric may be 50 maintained at a suitable tension between the two rollers.

In the practical working of the machine we have found that in the event of the fabric being held back through any cause as it travels 55 from the delivery to the feeding end of the machine, as frequently happens, it retards or slightly holds back the card-covered feed-roller while the driven pulley advances and carries the catch forward, it may be half a 60 tooth or more, whereby on the fabric being released or freeing itself the pull of the tension-roller causes the card-covered feed-roller to suddenly start forward again until the catch carried by the pulley engages with a 65 tooth of the ratchet-wheel, the result of this uncontrolled forward impulse being that the portion of fabric lying between the card-covered roller and the tension-roller receives a 70 little slack, and the proper tension of the fabric where the knife or knives operate is thus destroyed and renders same liable to make holes or slips.

The object of our invention is, therefore, to provide a retarding device for the feed-roller 75 and in connection therewith means for preventing further retardation of the feed-roller due to a pull on the cloth. In the particular embodiment of the invention such means is applied to prevent disconnection between the 80 feed-roller and the brake or retarding drive when the cloth is temporarily held or caught in passing from the scrap and under and over the guide-rollers and by such means to cause the jerk or sudden impulse permitted by the 85 released fabric under the pull of the tension-roller to be borne by the wrapping connection between the tension-roller and the driven pulley.

The novel features of our invention will be 90 fully described in the subjoined specification, and particularly pointed out in the following claims.

Referring to the drawings, Figure 1 is a side

elevation of the cutting end of a single-knife cotton cord or velvet cutting machine, such as shown and described in the United States Patent before referred to and embodying our improvements. Fig. 2 is a plan of Fig. 1, showing the near side of the machine only. Fig. 3 is a similar plan view to Fig. 2, but showing a four-knife machine with the additional drive required when a plurality of knives are employed. Fig. 4 is an enlarged longitudinal section taken on line 1 2, Fig. 2, showing one embodiment of our invention; and Fig. 5 is a similar longitudinal section taken on line 3 4, Fig. 3, showing a modified and preferred arrangement of our improvements.

In the accompanying drawings, and referring first to Figs. 1, 2, and 4, *a* is the machine side or frame; *b*, the feed-roller, which obviously may be provided with any usual non-slipping surface or be card-covered, as usual; *c*, the back rail; *d*, the tension-roller; *e*, the endless fabric to be cut, which is guided to and around the card-covered roller *b* by guide-rollers *f*, then guided by roller *f'* to the back rail *c*, from whence it passes to the tension-roller *d*, the knife or knives (not shown) operating between said roller and the back rail *c* to cut the pile, the fabric traveling forward around the rollers *g*, *g'*, *g''* and cutting itself onto a scray under the machine, from which scray it passes again to the feeding end of the machine, all in the usual way and as set forth in the patent above mentioned.

The fabric is drawn through the machine by the driven tension-roller *d* and tends to drive the card-covered feed-roller *b* by the frictional contact of the fabric therewith; but by a strap or belt *h*, passing around a pulley *h'* on the tension-roller shaft *d'* and around a pulley *i*, loose on the axis *b'* of the card-roller *b*, but adapted to be positively engaged rotatively with the shaft *b'* in a forward direction by a pawl *j*, carried by the pulley *i*, meshing with the teeth of the ratchet-wheel *b''*, fast on the shaft *b'*, the speed of the card-covered roller is retarded to approximately one-half that of the tension-roller in order to maintain the fabric at a suitable tension between the two rollers.

Any obstruction to the free traverse of the endless fabric to the card-roller *b* which will tend to momentarily hold or retard the speed of such roller below the normal causes the pawl *j* in the continued forward movement of the driven pulley to move out of mesh with the tooth of the ratchet-wheel *b''* with which it has been engaged and advance, it may be, half a tooth or more. On the fabric being released or freeing itself the pull of the tension-roller gives the card-roller, which is for the moment uncontrolled, a sudden start forward again at approximately the speed of the tension-roller until the catch or pawl *j* re-engages with a tooth of the ratchet-wheel *b''*, whereupon the card-roller is operatively

locked rotatively with the driven pulley in a forward direction and its motion retarded.

The result of the uncontrolled forward impulse of the card-covered roller causes the fabric lying between said roller and the tension-roller to be slackened a little, whereby the knife or knives is or are liable to make holes or slips therein.

To avoid the slackening of the fabric between the card-roller *b* and the tension-roller *d* under circumstances such as above named, it is necessary that while the connection between the cone-pulley and the card-roller should remain as before supplementary means should be provided for retaining a positive control of the card-roller and preventing a momentarily quicker rotation thereof than the speed of the retarding cone-pulley drive.

We will now describe the supplementary means we have devised for retaining an approximately positive control of the card-roller:

Referring first to Figs. 1, 2, and 4, in which one form of our improvements is shown, *k* is a circular plate or disk provided with a hub *k'*, through which is screwed a set-screw *k''* to secure the plate or disk to the hub *i'* of the driven pulley *i*. Against the face of the disk *k* abuts a leather washer *m*, passed loosely over the end of the card-roller shaft *b'*. In the outer end of the shaft *b'* is cut a keyway to receive a spline or key in the hub of a second disk or plate *n*, mounted on the shaft *b'* on the outer side of the washer *m*, the spline securing the disk rotatively to the shaft, but permitting it to move longitudinally thereon. The plate or disk *n* is held in engagement with the washer *m* by a strong spring *o* encircling the shaft *b'* and confined between said disk and a washer *p*, loosely mounted on the shaft *b'* and secured thereon by nut *p'*, screwed onto the end of the shaft *b'*. The tension of the spring can be increased by screwing the nut *p'* farther onto the shaft *b'*. The movable disk *n* is forced along with the leather ring or washer *m* into engagement with the disk *k*, fast on the hub of the pulley *i*, and is maintained in frictional driving contact therewith by the confined spring *o* to give a friction drive or coupling between the pulley *i* and the card-roller shaft *b'*. It will thus be manifest that should the fabric *e* be caught or temporarily held on its way to the card-roller *b* the friction coupling or connection between the card-roller shaft *b'* and the pulley *i* or brake-drive will overcome the resistance by remaining in engagement in a forward direction, and thus avoid the sudden start or forward impulse when the conditions become normal again, the drag on the cloth being taken up through the friction drive or coupling by the belt or strap *h*. The portion of fabric traveling between the card-roller *b* and tension-roller *d* is thus kept taut and at the required tension for the proper operation of the cutting knife or knives.

In the preferred embodiment of our invention shown at Fig. 5 the arrangement of the parts is simply the reverse of the arrangement described with reference to Fig. 4, the movable disk n' being in this instance secured rotatively by spline on the hub i' of the cone-pulley i and free to move laterally thereon and forced against the washer m to maintain the latter in frictional contact with the disk k' , secured by set-screw to the shaft b' by means of the strong spring o' , confined between the disk n' and a nut r , screwed onto the externally-screwed part b'' of the hub i' of the cone-pulley. The nut r is adjustable to vary the tension of the spring and is held in its adjusted position by a lock-nut r' .

The cone-pulleys shown in Figs. 4 and 5 are those employed in a single-knife machine and a four-knife machine, respectively, as will be obvious to those skilled in the art, and our invention is applied to both constructions of pulley precisely in the same way irrespective of any difference of construction in the pulley itself.

We prefer the frictional coupling device illustrated at Fig. 5 for the reason that the pulley can be supplied along with the friction-coupling to existing machines without having to remove the shaft b' from the machine, whereas in the arrangement illustrated at Fig. 4 a keyway must be cut in the shaft b' and a screw-thread chased on the end of said shaft, which entails unnecessary labor and expense.

It will be understood that the details of construction of our improvements may be varied, if desired, and that in place of the disks shown conical friction-disks may be used.

Having thus described our invention, what we claim as new, and desire to secure by Letters Patent, is—

1. In a cotton cord or pile cutting machine, a feed-roller to which the fabric to be cut is delivered, a driven tension-roller for drawing the fabric through the machine and thereby operating the feed-roller, a positively-driven retarding device for retarding the rotation of the feed-roller due to the movement of the cloth, and means for preventing further retardation of the feed-roller due to the pull of the cloth thereon.

2. In a cotton cord or pile cutting machine, a feed-roller to which the fabric to be cut is delivered, a driven tension-roller for drawing the fabric through the machine and thereby operating the feed-roller, a positively-driven retarding device having operative engagement with said feed-roller when rotating in a forward direction, and a friction-clutch connecting the retarding device to said feed-roller to prevent further retardation of said feed-roller due to the pull of the cloth thereon.

3. In a cotton cord or pile cutting machine, a feed-roller to which the fabric to be cut is delivered, a driven tension-roller for drawing the fabric through the machine and operating

the feed-roller by the drag of the fabric thereover, a positively-driven retarding device comprising a pulley loosely mounted on the feed-roller shaft, a pawl-and-ratchet connection between the said pulley and said shaft for transmitting the retarding action of said pulley to the feed-roller, and means for preventing disengagement of the pawl and ratchet and consequent further retardation of the feed-roller due to the backward pull of the cloth.

4. In a cotton cord or pile cutting machine, a shaft, a feed-roller thereon, to which the fabric to be cut is delivered, a driven tension-roller for drawing the fabric through the machine and thereby operating or turning the feed-roller, a driven retarding device comprising a pulley mounted on the shaft of the feed-roller, a ratchet-and-pawl connection between the said pulley and shaft for transmitting the retarding action of said pulley to said shaft and feed-roller, and a friction-clutch connection between the said shaft and pulley for preventing disengagement of the ratchet and pawl and consequent further retardation of the feed-roller due to the backward pull of the cloth.

5. In a cotton cord or pile cutting machine, a shaft, a card-covered feed-roller loosely mounted thereon, a fixed rail, a driven tension-roller for drawing the fabric through the machine and thereby operating to turn the card-covered feed-roller, a pulley loosely mounted on the feed-roller shaft and provided with a catch or pawl, a ratchet-wheel fixedly mounted on the feed-roller shaft and engaged by said pawl or catch, means for driving said pulley to retard the rotation of the feed-roller, and a friction-clutch connection between the said pulley and feed-roller shaft for preventing relative rotative movement of the ratchet-wheel and pawl or catch and consequent further retardation of the feed-roller due to the backward pull of the cloth.

6. In a cotton cord or velvet-pile cutting machine, a shaft, a card-covered feed-roller loosely mounted thereon, a driven tension-roller for drawing the fabric through the machine and thereby operating to turn the feed-roller, a driven retarding device for retarding the rotation of the feed-roller due to the movement of the cloth, and means for preventing further retardation of the feed-roller due to the backward pull of the cloth, said means comprising a pair of friction-disks, one being mounted on the feed-roller shaft and the other connected to the driven retarding device.

In testimony whereof we affix our signatures in presence of two witnesses.
